DESIGN FOR A COMBINATION SALT AND PEPPER SHAKER

Martin Cusanelli, Astoria, Long Island, N. Y.

Application March 7, 1944, Serial No. 112,809

Term of patent 14 years

(Cl. D44—22)

To all whom it may concern:

Be it known that Martin Cusanelli, a citizen of the United States of America, residing at Astoria, Long Island, in the county of Queens and State of New York, has invented a new, original, and ornamental Design for a Combination Salt and Pepper Shaker, of which the following is a specification, reference being had to the accompanying drawing, forming part thereof.

Fig. 1 is a front elevational view of a combination salt and pepper shaker, showing my design.

Fig. 2 is a top plan view, and

Fig. 3 is a bottom plan view thereof.

Fig. 4 is a horizontal sectional view, taken along line 4—4 of Fig. 1, looking in the direction of the arrows.

The cross hatching shown to the left of Figs. 1, 2 and 4, represents a color contrasting with that of the right side of the combined salt and pepper shaker.

I claim:

The ornamental design for a combination salt and pepper shaker, as shown and described.

MARTIN CUSANELLI.
